UNITED STATES PATENT OFFICE.

LE ROY K. SHERMAN, OF CHICAGO, ILLINOIS.

EXCAVATING-MACHINE.

1,044,090.

Specification of Letters Patent. Patented Nov. 12, 1912.

Application filed October 9, 1908. Serial No. 456,966

To all whom it may concern:

Be it known that I, LE ROY K. SHERMAN, a citizen of the United States, residing at the city of Chicago, in the county of Cook 6 and State of Illinois, have invented a new and useful Improvement in Excavating-Machines, of which the following is a specification.

My invention is an improvement in machines for excavating earth and other materials.

In the construction of canal cuts or channels and the like this is frequently done by excavators of the "drag line bucket" 15 type, which operates by drawing a skip or bucket, provided with a cutting lip, over and through the material to be excavated, by means of a stationary hoisting engine and a connecting rope. Much inconvenience and delay are occasioned in the use 20 of such drag line scrapers, because there is no means provided for positively directing and steadyng the cutting edge which is therefore frequently turned aside or thrown 25 out of the earth by meeting some slight obstruction which would otherwise be cut through or gathered up.

My invention provides an apparatus by which the cutting edge of the bucket is 30 positively and squarely presented to the material and the loading and dumping are performed with speed and certainty.

The apparatus is simple and cheap, is 35 constructed in many respects on the lines of existing machines, is not likely to get out of order, and the operations of the bucket are at all times under positive control of the engineman.

The principles of my invention are illustrated in the drawings, in which

Figure 1 represents a cable way, including my improvements, the bucket being represented as filled. Fig. 2 shows the bucket in the act of entering the earth to be filled; 45 Fig. 3 represents the bucket preparatory to dumping, and Fig. 4 represents the car and bucket arm with details of construction.

Further describing my invention with reference to the drawings, A—A' represent 50 towers of the ordinary and usual construction mounted on trucks and adapted to be moved as desired. The two towers may be connected by the main cable 1, securely attached to the ends thereto, and provided 55 with such means for taking up the slack as may be desired. A car 2 which is quite

elongated in the line of its operation is provided with pulleys 3—3 by which it is suspended on the main cable 1. A conveying rope 4 is attached to one end of the car 60 2, passes over the pulley 5 on the tower A'; thence across the span between the two towers over the pulleys 6, and another pulley (not shown) alined therewith; thence over the drum 7 of the hoisting engine 8, upon 65 which are given sufficient turns to prevent slipping by friction. It is then carried upward and around the pulley 9, and thence to the car 2, to the end of which it is attached. The bucket 10, provided with the 70 cutting edge 11, has an arm 12, rigidly secured thereto. Said arm may have two members 13, spaced from each other, so as to include the car 2 between them, and the latter is provided with stops 15 at some 75 distance from each other, by which the scoop arm 12 may be retained upon the car, but between which stops it may have free horizontal and vertical motion. A cable 16 is secured at one end to an eye 17 on the 80 underside of the car 2. The said cable is carried around a pulley 18 on the underside of said car, and thence downwardly and around a drum 19, which may be actuated by a crank on the squared shoulder 85 20. Backward or downward motion of said drum being controlled by dog 21 in connection with a ratchet wheel, a means is provided by which the downward movement of the scoop is positively limited, while its 90 movement upward is not interfered with. But it will be seen that any rotary motion of the bucket about its cutting edge is prevented by the otherwise rigid connection thereof to the arm 12 and the car 2. 95

A hoisting and guiding rope 25 is provided, which is attached to the eye 26 on the bucket, passes over the pulley 27 on the car 2, and thence over the pulley 28 on the tower A to the drum 29 of the engine. The 100 drag rope 30 may be attached to the eye 26 and is connected directly to the engine drum 31.

The bucket 10 has a false bottom 10' which may be hinged at 10'' and be adapted 105 to be locked and tripped in the ordinary manner. A very simple and cheap construction of the bucket arm and car is to employ channel bars of standard shape for their practical members. In the bucket arm 110 the members 13 have the flanges turned outwardly, while in the car the members 2'.

are turned inwardly and secured together by plates 2" riveted thereto.

The initial position of the bucket for making the cut is shown in Fig. 2, the same having been dropped at the proper point by the car and the lifting rope. The latter controls the depth of cut, while the drag rope forces the bucket in until filled, when the parts assume the position shown in Fig. 10 1. The lifting rope 25 is then wound up by the drum 29 while the drag rope is slacked. The conveyer rope is then shifted by the drum 7 until the car and bucket are carried over the spoil bank, where the parts 15 are substantially in the relative position shown in Fig. 3. The bucket is then dumped by opening the hinged bottom 10' and the car again run out over the work until, upon reaching the proper position, the bucket is 20 again dropped and the operations described again repeated.

I have shown and described my invention with reference to a cable way adapted to support the car, but any other means of 25 supporting the car may be used, and, under certain circumstances, the same or any independent support may be omitted altogether.

I claim:

30 1. In an excavating apparatus, the combination of supports spaced from each other, a flexible cable way connecting the supports, a car suspended from the cable way to ride thereon, a conveyer rope connected at its 35 respective ends to the respective ends of the car and passed over sheaves on the supports and over a winding drum to actuate the car on the cable way, a bucket arm comprising members spanning the car and the 40 conveyer rope, means for operatively moving the bucket arm, a bucket carried by said arm, means connected to the car and the arm for moving the latter independently of and with respect to the car, and means connected to the bucket for giving forward 45 and upward movement thereto.

2. In an excavating apparatus, the combination of supports spaced from each other, a flexible cable way secured at each end to 50 the supports, a car suspended from the cable way to ride thereon, a conveyer rope con-

nected to each end of said car and passed over sheaves on the supports and over a winding drum to actuate the car on the cable way, a bucket arm having a plurality of 55 members extended upwardly one on each side of the car and conveyer rope, said arm having free movement independently of the car, means for operatively moving the bucket arm, and means adjustably attached 60 to the car and to the arm for limiting the downward movement of the arm.

3. In an excavating apparatus, the combination of supports spaced from each other, a flexible cable way secured at each end to 65 the supports, a car to ride on the cable way, a conveyer rope connected to the respective ends of said car and passed over sheaves on the supports and over a winding drum to actuate the car on the cable way, a bucket 70 arm adjustably related to the car and having independently vertical and longitudinal movement with respect thereto, a hoisting rope connected with the arm and passed over sheaves on the car and on one of the 75 supports to a winding drum, and a drag rope connected to the arm and to a winding drum.

4. In an excavating apparatus, the combination of supports spaced from each other, 80 a flexible cable way secured at each end to the supports, a car to ride on the cable way, a conveyer rope connected at its ends to the respective ends of said car and passed over sheaves on the supports and over a winding 85 drum to actuate the car on the cable way, a bucket arm having a plurality of members extended upwardly on each side of the car and the conveyer rope, a hoisting rope connected to the arm and passed over sheaves 90 on the car and on one of the supports to a winding drum, and a drag rope connected to the arm and to a winding drum.

In witness whereof, I have hereunto set my hand, this 5th day of October A. D. 95 1908, in the presence of two subscribing witnesses.

LE ROY K. SHERMAN.
